Fig. 5.

UNITED STATES PATENT OFFICE.

CHARLES D. FREY, OF CHARLOTTE, NORTH CAROLINA.

COMBINATION GUIDE.

Application filed August 18, 1926. Serial No. 129,998.

This invention relates to a combination guide particularly adapted for use by brick layers or other masons in the construction of walls from brick, stone, concrete or the like.

The main object is to provide a novel means for use in the relations mentioned which will serve as a gage to regulate the brick work or similar work and to render the matter of lead raising and twiggling easier, and to a considerable extent avoiding many steps and acts essential under present practice.

Additional objects and advantages will become apparent from a consideration of the description following taken in connection with accompanying drawings illustrating an operative embodiment.

In said drawings:

Figure 1 is a view in perspective illustrating the apparatus in connection with a wall under construction;

Figure 2 is a plan view of the corner frame;

Figure 3 is a side view of said frame;

Figure 4 is a side view of said frame taken at a right angle to Figure 3;

Figure 5 is a vertical sectional view taken through the corner frame on the line 5—5 of Figure 2;

Figure 6 is a horizontal sectional view taken through the side frame on the line 6—6 of Figure 4, slightly below the plane at which it rests on the wall and looking in an upward direction;

Figure 7 is a side elevation of the angle bar;

Figure 8 is a plan view thereof;

Figure 9 is a side elevation taken at a right angle to Figure 7; and

Figure 10 is a vertical sectional view taken on the line 10—10 of Figure 7, through the elongated slot of the gage and associated parts.

Referring specifically to the drawings, a corner frame is provided as at A for instance having upper and lower angle brackets 11 to the arms of which uprights 12 are bolted as at 13. The uprights 12 have horizontal portions offset as at 14, and upstanding guides 15. Said uprights are efficiently braced as by bars 16 bolted in place as at 17. Certain of the bolts 17 fasten outwardly extending brackets 18 to the guide bars 15. Brace wires or the like 19 are fas-

tened to the upper ends of the bars 15 and to said brackets 18.

Vertically adjustable on the bars or portions 15 are line holders consisting of bars having cleats 21 thereon surrounding the portions 15 and accommodating certain wing screws 22, by which they may be fastened by binding, in any adjusted position, along said bars. The upper edges of the holders 20 are preferably notched as at 23 to accommodate the fastening of the lead line thereto.

Diagonal brace straps 25 are fastened as at 26 by means of bolts, to the portion 14 and as at 27 by means of bolts to braces 28 which are bolted at 29 to triangular plates 30 and which plates 30 are bolted at 31 to base bars 32, bolted at 33, to the ends of the lower angle member 11. At suitable intervals, hooked rods 34, are pivoted to the various parts, such as the braces 28 and plates 30, which are used to penetrate at their bills 35 into mortar or cement, to aid in holding the device in place.

Bridging the straps 25 is a plate 36, fastened in place by the said bolts 26 and which plate has a notch as at 37 in which a plumb bob or other leveling device 38 may be suspended. This device consists of a bob 39 and a cord 40, having a knot at 50, which rests on the plate 36.

Adapted to rest on the wall itself, of course after it has been built up a number of courses, for instance 7, is a rest plate 51, which is arranged diagonally to and rests on the arms of the upper angle 11, and which has its terminal as at 52, returned and clinched over the brace straps 25, in order to position it and hold it in place.

It will thus be seen that the device rests on the wall in the course of construction, by the engagement of plate 51 with the top thereof and also the angles 11 are in intimate contact with the angular sides of the wall at the corner thereof. The fastening is supplemented, when desired, by the hooks 34 which are used to penetrate the mortar or cement. The lead line, is fastened at any proper location to the holders 20 by tying the same therearound, lateral movement of the lead being prevented by the notch 23 with which the lead is engaged. Such holders may be adjusted to any vertical position through manipulation of the wing screws 22 associated therewith.

It will be noted that the parts below the

plate 51 are connected together for the most part by bolts which permit certain of them to be removed when it is desired to fold or collapse the structure so that it will occupy 5 minimum space.

Used jointly with the corner frame A is a twitting bar generally designated B. This bar is adapted to assume a vertical position as shown in Figure 7 against the side of 10 the wall and it has a top plate 60 adjustably disposed across the upper end of the bar proper 61, passing for instance through a loop bracket 62 fastened to the bar and held in adjusted position as by means of a 15 binding screw 63 carried by the bracket. The outermost end of the plate 60 is formed into a downturned handle or lug 64 and the latter may be resilient, if desired. A gage in the form of a plate 66 is fastened to the 20 bar 61 for adjustment to any height and in this connection has an elongated slot 67 through which a winged screw 68 passes in order to engage the bar and bind the gage in adjusted position against it. Such gage 25 has a loop 69 at its upper end provided with an eye 70 therethrough through which the lead line, which as previously described is attached to the holder 20, passes and which lead line may be fastened against slippage 30 by tying it in an eyelet 71 of a bracket 72, fastened to one side of bar 61. This bar 61 may also have hooks 73, pivoted thereto, and provided with bills 74 adapted for penetration into cement or mortar, to aid in 35 securing the bar in place.

The bar 61 is essentially a plumb bob since it carries a bob as at 75, in a suitable opening of the bar and which is suspended by a cord 76 fastened to the top of the bar.

40 L-shaped supports 76 are fastened adjustably as to height, by means of wing screws 77 passing through elongated slots 78 thereof and into the bar 61. These supports by reason of their shape have laterally extending arms which are adapted to engage and 45 rest on cement columns, when the device is so used that the bar is disposed between them. In other instances, these supports are omitted.

50 Various changes may be resorted to provided they fall within the spirit and scope of the invention.

I claim as my invention:

1. A device of the class described having 55 upper and lower angle brackets to engage the corners of a wall, uprights securing said brackets together, means carried by the upper bracket to rest on the wall and support the device, said uprights having laterally offset portions, bars rising from said portions, and means carried by said bars to hold leads.

2. A device of the class described having 60 upper and lower angle brackets to engage the corners of a wall, uprights securing said

brackets together, means carried by the upper bracket to rest on the wall and support the device, said uprights having laterally offset portions, bars rising from said portions, means carried by said bars to hold leads, and brace elements connected together and to both of said angle brackets. 70

3. A device of the class described having upper and lower angle brackets to engage the corners of a wall, uprights securing said 75 brackets together, means carried by the upper bracket to rest on the wall and support the device, said uprights having laterally offset portions, bars rising from said portions, means carried by said bars to hold leads, brace elements connected together and to both of said angle brackets, and anchor hooks carried by the brace members. 80

4. A device of the class described having upper and lower angle brackets to engage 85 the corners of a wall, uprights securing said brackets together, means carried by the upper bracket to rest on the wall and support the device, said uprights having laterally offset portions, bars rising from said portions, 90 means carried by said bars to hold leads, brace elements connected together and to both of said angle brackets, brace straps connected to the angle brackets and to said offset portions, means connected to said straps 95 to rest on a wall, and a plumb bob supporting member secured to said brace straps. 100

5. A device of the class described having upper and lower angle brackets to engage 105 the corners of a wall, uprights securing said brackets together, means carried by the upper bracket to rest on the wall and support the device, said uprights having laterally offset portions, bars rising from said portions, means carried by said bars to hold leads, 110 brace elements connected together and to both of said angle brackets, brace straps connected to the angle brackets and to said offset portions, means connected to said straps to rest on a wall, a plumb bob supporting member secured to said brace straps, braces extending from the lower angle bracket to the upper angle bracket, other brackets secured to and extending outwardly of the uprights, and brace means extending from the last mentioned brackets to the upper ends of the uprights. 115

6. A device of the class described comprising a bar, means adjustably mounted on the bar for fastening of a lead line thereto, means to support the bar on a wall, comprising a plate adjustably mounted on the top of the bar, and hooks carried by the bar. 120

7. A device of the class described comprising a bar, provided with a plumb bob, a gage vertically adjustable on said bar and adapted for fastening of a lead line thereto, means on the bar to which the lead line is adapted to be tied, and a plate at the top of the bar to rest on a wall. 125 130

8. A device of the class described comprising a bar, provided with a plumb bob, a gage vertically adjustable on said bar and adapted for fastening of a lead line thereto, 5 means on the bar to which the lead line is adapted to be tied, a plate at the top of the bar to rest on a wall, said gage having an elongated slot, a fastening passing through

said slot to secure it to the bar, and adjustable supporting members on the bar, a loop 10 guide at the top of the bar through which said plate passes, a depending end on said plate, and a binding screw carried by the guide to engage the plate.

In testimony whereof I affix my signature.
CHARLES D. FREY.
